THE NORRIS PETERS CO., PHOTO-LITHO., WASHINGTON, D. C.

UNITED STATES PATENT OFFICE.

ANNABEL CRINNION, OF FLUSHING, NEW YORK.

LIFE-SAVING SUIT.

1,140,025.

Specification of Letters Patent.

Patented May 18, 1915.

Application filed September 18, 1914. Serial No. 862,353.

To all whom it may concern:

Be it known that I, ANNABEL CRINNION, a citizen of the United States, residing at Flushing, Long Island, in the county of 5 Queens and State of New York, have invented certain new and useful Improvements in Life-Saving Suits; and I do hereby declare the following to be a full, clear, and exact description of the invention, such as 10 will enable others skilled in the art to which it appertains to make and use the same.

This invention relates to life saving suits and the primary object of the invention is the provision of a suit for protecting a person 15 against fire or smoke so as to enable them to be lowered or carried from a building which is being devastated by fire without personal injury to the party.

Another object of this invention is the 20 provision of a suit which may have an inner layer of buoyant material such as cork or the like, and provided for the purpose of saving lives at sea which buoyant material will cause the person upon which the suit is 25 mounted to float upon the water.

A still further object of this invention is the provision of gloves or hand coverings formed upon the suit which are provided with a plurality of grooves formed in the 30 palm thereof for permitting a person to slide down a rope without burning or abrading his hands.

With the foregoing and other objects in view, this invention consists in such novel 35 features of construction, combination and arrangement of parts as will be hereinafter more fully described, illustrated in the accompanying drawings and claimed.

In describing the invention in detail reference 40 will be had to the accompanying drawings wherein like characters designate like or corresponding parts throughout the several views, and in which:—

Figure 1 is a view of the improved life 45 saving suit showing parts thereof broken away to expose the internal construction of the suit, Fig. 2 is a cross sectional view on the line 2—2 of Fig. 1, and Fig. 3 is a cross sectional view on line 3—3 of Fig. 1.

Referring more particularly to the drawings, 50 1 designates the body of the improved life saving suit, which is formed of canvas or other suitable material and is substantially sack shaped, having arms 2 and 3 55 formed thereupon in the proper position for receiving a person's arms and a helmet or

head portion 4 formed upon the upper end of the body portion and connected thereto by a neck band 5.

The helmet 4 has a plurality of small perforations 6 formed therein, which are provided for the permitting of air to enter the helmet to permit of the breathing of the person upon which the suit is mounted. The helmet 4 has a slot 7 formed therein, in 60 which slot is mounted isinglass or other transparent material for position in front of the eyes of the person to permit them to see through the helmet. The helmet 4 has cushions mounted therein against which the 65 head of the person wearing the suit rests. A metallic plate 9 is also mounted in the helmet and has a ring 10 secured thereto, which ring is provided for engagement with a rope, hook or the like for lowering a person 70 out of a building.

The body portion 1 of the life saving suit is provided with a slit or opening formed therein, the marginal edges of which overlap as is shown at 11 in Fig. 1 of the drawings, and the overlapping marginal edges of this slit are fastened together by ordinary glove fasteners 12. The slit is provided to permit a person to get into the life 80 saving suit.

When it is desired to use the life saving suit in connection with buildings for permitting a person to escape therefrom in case of fire, a weight 13 is mounted in the lowermost portion of the body 1 so as to cause 90 the suit to fall bottom down and hold a person in a proper position when they are escaping from a building. Cushions 14 are mounted upon the upper surface of the weight 13 for cushioning the feet of the person 95 in the suit.

The body portion 1 of the suit has any desirable number of pockets 15 formed in the inner surface thereof for containing valuables or like articles when the person is escaping from either a fire infested building or 100 sinking ship.

When the suit is used for life saving purposes in case of fire, the fabric, which may be canvas, or other suitable material of 105 which the suit is formed is coated with a non-combustible substance to prevent the same from catching fire from the flames in the building.

The gloves or hand coverings 16 and 17 110 which are formed at the terminals of the arms 2 and 3 may be either of mitten or

glove shape, as desired and may have a layer of cork or other similar material formed on the palms thereof, which layers 18 of cork are provided with grooves 19 formed therein for receiving a rope, cable or the like to permit of a person sliding down a rope without abrasing his hands.

When it is desired to use the life saving suit for saving lives at sea, in case of a sinking ship, the entire suit is lined with a layer of cork as indicated at 20, or any other suitable buoyant material may be employed, and the weight 13 is removed from the bottom of the suit, so as to permit the suit to 15 float on the water.

In reducing the invention to practice, certain minor features of construction, combination and arrangement of parts may necessitate alterations to which the patentee is 20 entitled provided such alterations are comprehended within the scope of what is claimed.

What is claimed is:—

1. In a life saving suit, a substantially 25 sack shaped body portion, arms formed upon said body portion, gloves formed at the terminals of said arms, layers of cork formed upon the palms of said gloves.

2. In a life-saving suit, a substantially 30 sack shaped body portion, arms formed upon said body portion, gloves formed at the terminals of said arms, layers of cork formed upon the palms of said gloves, and a weight mounted in the lowermost portion 35 of said body portion.

3. In a life-saving suit, a substantially 40 sack shaped body portion coated with non-combustible material, arms formed upon said body portion, gloves formed at the terminals of said arms, layers of cork formed upon the palms of said gloves, a weight mounted in the lowermost portion of 45 said body portion, a detachable cushion mounted in the lower portion of said body portion and upon said weight.

4. In a life saving suit, a substantially sack shaped fabric body portion coated with non-combustible material, arms formed upon the sides of said body portion, hand coverings formed at the terminals of said arms, a layer of cork mounted upon the palms of said hand coverings, a helmet secured to the uppermost portion of said body portion, a neck band connecting said helmet and said body portion, and a weight 55 mounted in the lowermost portion of said body portion.

5. In a life-saving suit, a substantially sack shaped body portion coated with non-combustible material, arms formed upon 60 the sides of said body portion, hand coverings formed at the terminals of said arms, a layer of cork mounted upon the palms of said hand coverings, a helmet secured to the uppermost portion of said body portion, a 65 neck band connecting said helmet and said body portion, a weight mounted in the lowermost portion of said body portion, cushions mounted in the lower portion of said body portion and resting upon said weight, 70 and a detachable cushion mounted in the upper portion of said helmet.

6. In a life-saving suit, a substantially sack shaped fabric body portion, arms formed upon said body portion, hand coverings formed at the terminals of said arms, a helmet secured to the uppermost portion of said body portion, a neck band connecting said body portion and said helmet, a layer of buoyant material secured to the inner surface of said body portion and said arm, and detachable cushions mounted in the upper portion of said helmet and the lowermost portion of said body portion.

In testimony whereof I affix my signature 85 in presence of two witnesses.

ANNABEL CRINNION.
